UNITED STATES PATENT OFFICE.

WILLIAM H. BARRIE, OF WALLA WALLA, WASHINGTON.

IRONING TABLE.

Refiled for abandoned application Serial No. 11,626, filed February 26, 1925. This application filed July 3, 1926. Serial No. 120,443.

This invention relates to ironing tables, of the closable type, and has as one of its objects to provide an ironing table that will close in a space equalling the width of a 5 studding so that it may be incorporated in the building of houses, or that may be contained in a cabinet attachable to a wall, with a minimum of projection therefrom, and yet provide space for a sleeve board without 10 interfering with the action of the ironing table.

Another object of the invention is to provide a closable ironing table that is simple yet positive in operation, and that may be 15 opened or closed, or adjusted as to height, with a minimum of effort.

A further object of the invention is to provide an ironing table that is relatively cheap to construct and that has a maximum of rigidity when open.

With these and other objects of the invention in view reference is now had to the accompanying drawings in which

Fig. 1 is a sectional elevation of the device showing an ironing table and sleeve board in the open position;

Fig. 2 is a similar view to Fig. 1 showing the sleeve board closed and the ironing table partly closed;

Fig. 3 is a similar view to Fig. 1 showing the ironing table closed;

Fig. 4 is a front elevation of the device showing the ironing table in the closed position;

Fig. 5 is an enlarged view of a fragment of the device showing the slots, notches and movable parts therein; and

Fig. 6 is a similar view to Fig. 5 showing the movable parts in a slightly changed position.

Having reference to the drawings like numerals refer to like parts throughout the several views and the numeral 1 refers to a cabinet comprising a slotted frame 2, a top piece 3, a shelf 4, a cross piece 5, and a back 6.

The top piece closes the upper part of the frame and the shelf 4 may be utilized to support an iron or other object, and also as a spreader for the frame.

The shelf 4 may carry a spring catch 7 or the catch may be attached to the back 6, as is the spring catch 8, the purpose of both of which catches will be explained subsequently.

The cross piece 5 braces the lower end of 55 the frame.

The back 6 is preferably made of thin material such as fiber board or veneer to save space, as the whole depth of the cabinet must be no greater than the depth of the studding plus the plaster on one side of the wall. 60

The frame is slotted, as at 9, the slot being positioned centrally of the frame and in the lower half thereof, as shown.

Operably mounted in this slot is a free moving unit, forming a triangle when open, 65 consisting of a closable ironing table 10 comprising a board 11 forming one side of the triangle, a cleat 12 rigidly attached to its under side, and attached to this cleat by hinges 12^a (and thus to the board) is a brace member 70 13, forming the second side of the triangle, and comprising preferably a pair of legs 14 strengthened by means of the members 15, and rigidly attached to the inner end of both the board and the brace member are cross 75 members 16 and 17 respectively, each of which cross members being provided on their ends with trunnions 18 that in turn are slidably mounted in the slots 9.

The board and brace members are made 80 of a certain thickness for economy, and the cross members 16 and 17 are of greater thickness to provide for trunnions of ample size and strength, and at the same time to provide for positioning the trunnions eccentrically on the end of the cross members so that the cross member will form a shoulder 85 19 to prevent any side play of the board or brace member.

By this means the slot 9 may be of ample 90 width to receive a trunnion of a diameter equal to the thickness of the board 11 and yet by the eccentric position of the trunnion will form a shoulder to prevent the board from entering the slot to become caught or 95 jammed therein.

The slots are cut in a manner to form a plurality of sets of oppositely disposed adjusting notches 20 communicating with the slots, and in this case a group of three notches 100 are shown wherewith three adjustments may be obtained. A set of notches comprises any notch of the upper group with the corresponding notch of the lower group, and the notches are oppositely disposed as the upper 105 group is on the forward side to receive the trunnions of the board, while the lower group is on the rearward side of the slot to receive the trunnions of the brace member.

The upper group is designed to fixedly re- 110

ceive the trunnions of the board while the lower group will receive the trunnions of the brace member, and both in a manner to provide for a direct pull or push caused by the 5 weight of the board when open.

Each set of notches is arranged the same distance apart and to provide for easy adjustment of the board therein the brace member 13 is entirely supported from the board 10 11 by means of a chain 21 or other similar flexible and folding means (which supports the free end of the brace), and said hinge 12^a, the chain being adjusted to maintain the free end thereof at a distance corresponding to the 15 distance apart of the notches of the respective sets and forming with the ironing table and the brace member the completed triangle referred to.

It is now apparent that by positioning the 20 board in the notch at the height desired that the trunnions of the brace member will automatically enter their respective notches, and upon releasing the board that it will at once become fixed and stable.

25 Where a sleeve board 22 is included a brace 23 will be secured to the board by a hinge 24 to support it.

The sleeve board 22 is set out slightly away from the back to provide for free movement 30 on its trunnions, and its outermost part, the hinge 24, projects over the center of the slot 9 when the sleeve board is in folded position and hence would interfere with shutting the board 11 were not provision made for this 35 purpose, such provision being the eccentrically positioned trunnions 18, and other provisions now to be explained.

Now in closing the ironing table the ironing board will strike the hinge 24 and the 40 board will assume an angle approximating that shown in Fig. 6. In order then to bring the board to a vertical position relief notches 25 (the relief notches also having an area less than the area of the ends of the cross members) are provided on the front side of the slot, and in a position to receive the trunnions 45 when the top of the board is pressed inward against the hinge, the latter acting as a fulcrum and the trunnions moving outward as 50 the top of the board moves inward.

The relief notches are also intended to provide ample play for the trunnions which is required for easily manipulating the board when drawing it out and are tapered at their 55 upper side, as at 26, to guide the trunnions out of the notches and into the slots during that operation.

It is now evident that whether the sleeve board is employed or not the relief notches

are highly important as they offer ample play 60 to enable the board to seat easily when closed and to be easily withdrawn.

In use the board is withdrawn by grasping its upper part and pulling outward. The board now falls forward to the position shown 65 in Fig. 2, and by pressing on its outer end the trunnions of the board travel upward in the slots and finally enter the lower notch of the upper group of notches, this being the corresponding notch to the lowest notch of the 70 lower group in which the trunnions of the brace member now seat.

By this movement the chain is also tightened and holds the parts a proper distance apart so that to adjust the board as to height 75 it is only necessary to press the board inward and raise or lower it to the desired notch and then release it when the trunnions of the brace member will enter the corresponding notch of its group.

The sleeve board may be constructed and operated in a similar manner. Owing to the relatively small amount and nature of the work done on this board it is found that its height within a few inches makes no material 85 difference, and hence I prefer to mount the sleeve board pivotally in the frame, in a fixed rather than an adjustable manner to reduce the cost of manufacture.

A chain 27 however is also provided on 90 the sleeve board so that its brace member will seat automatically in the cross piece 28 placed against the back for the purpose.

The above mentioned catches 7 and 8 will retain the boards in a vertical position when 95 closed.

This application is refiled for abandoned application Serial No. 11,626, filed February 26, 1925.

Having thus described my invention, I 100 claim:—

In an ironing table the combination with a vertical cabinet having opposed slots in the side walls, of a unit consisting of an ironing board having trunnions slidably mounted in 105 the slots of said cabinet, a brace member hingedly secured at one end to said board and at its other end slidably mounted in the said slots, and a flexible element connecting the inner ends of said board and said brace member, said slots being formed to provide upper and lower sets of adjusting notches adapted to receive said board and said brace member, and each upper slot and its corresponding lower slot being positioned a distance apart 110 equal to the length of the flexible element.

In testimony whereof I affix my signature.

WILLIAM H. BARRIE.
